(57) **CLAIM**

The ornamental design for electric connector assembly, as shown and described.

DESCRIPTION

FIG. 1 is a front elevational view of electric connector assembly showing our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof;

FIG. 7 is a top and right front perspective view thereof; and,

FIG. 8 is a bottom and left rear perspective view thereof.
